CASKET LIGHT SUPPORT

Filed Sept. 1, 1926

Fig. 1.

Patented June 5, 1928.

1,672,317

UNITED STATES PATENT OFFICE.

EDWARD E. HILL, OF INDIANAPOLIS, INDIANA.

CASKET-LIGHT SUPPORT.

Application filed September 1, 1926. Serial No. 133,003.

Heretofore much difficulty has been experienced in properly supporting lights in connection with caskets in which bodies are laid out, as at funerals and where it is desired that the appearance of the room and decorations shall be of most appropriate and desirable character.

The object of my said invention is to provide a support for lights adapted for use for such purposes, whereby such a light is provided that may be conveniently and appropriately located and supported in a manner that will be not only convenient to mount in place and remove but also will support the light in a position that will not interfere with a view of the body in the casket and will permit of decorations of any character appropriate for the occasion, all as will be hereinafter more fully described and claimed.

Referring to the accompanying drawings which are made a part hereof and on which similar reference characters indicate similar parts:

Figure 1 is a perspective view of the light support and shade frame embodying my said invention,

Figure 2 is a side elevation thereof with parts broken away,

Figure 3, a detail perspective of the lamp support, and

Figure 4, a detail view of the bale-like member for supporting the shade.

In said drawings the portion marked 10 indicates a main support or bracket; 11 a supplemental support hinged thereto and 12 a shade frame.

The bracket 10 consists of a curved arm having an angle iron base 15 adapted to engage the corner of the casket lid when the lid is raised. The supplemental support 11 is preferably of thin metal and is hinged to the base 15 so that it may hang at any angle in respect to said base that may be required in order to fit or lie against the surface of the casket lid. Said part 11 is covered with fabric of appropriate character, such as plush or similar material, which extends for a distance beyond the part 11 and is provided with a weighted end 16 of sufficient weight to overbalance the weight of the shade and light on the projecting end of bracket 10.

The shade frame 12 comprises a main frame of substantially rectangular form

having angular corners and curved bars extending upwardly therefrom to a smaller frame member 18 of appropriate form at the upper end. A bale-like cross member 19 is connected with the ends of said member 18 and extends through a perforation in the lower end of arm 10 and is held by a set screw 20 adapted to impinge against the side thereof and hold the member rigid and said shade at whatever angle desired.

Said shade frame is covered with material of any appropriate character for the purpose, such as silk of a color that will tone the light as may be desired, and bearing such ornamentation as may be desired for any purpose. In the drawing I have indicated a rosette on the front side of the shade and on this rosette an emblem or badge 21 may be pinned, such emblem or badge being to denote any order or organization to which the deceased may have belonged. This, however, is only in the way of a suggestion as to how the lamp shade may be utilized not only for the purpose of decoration but for the other purposes as well.

To a cross-bar 22 supported by two of the members 12 a lamp socket 23 of any usual or appropriate construction may be mounted in which a lamp 24 is mounted, such lamp socket being connected by wires 25 which extend underneath the arm 10 over the support 15 and under the covering on the hinged arm 11 to a point where an attaching socket 26 may be supported, by means of which an electrical connection may be established with the light from any source of supply through the medium of an ordinary connecting cord, all as will be readily understood.

By this construction of device, as will be readily understood, a light may be appropriately supported in connection with a casket and in a manner to be entirely out of the way of floral and other decorations and at the same time in a position which will be of greatest advantage not only for the purpose of illumination but also for purposes of suitable decoration.

It will be obvious to those skilled in the art that various changes may be made in my device without departing from the spirit of the invention, and I, therefore, do not limit myself to what is shown in the drawings and described in the specification, but only as set forth in the appended claims.

Having thus fully described my said invention what I claim as new and desire to secure by Letters Patent is:

- 5 1. A casket light support comprising an arm, a frame for a light pivoted to one end of said arm, a base rigidly mounted at the other end of said arm for engaging the edge of a casket lid, said base having a depending portion for engaging the front of the elevated casket lid and a rearwardly extending portion corresponding to the thickness of said lid, and a flat strap hinged to the rear end of said rearwardly extending portion and having a weight at its lower end, said 10 weight being heavier than the arm and members supported thereby and serving to overbalance said arm and light frame and maintain said base in fixed position on its support, substantially as set forth.
- 15 2. A light support comprising a bracket

having a rigid support engaging member at one end and a frame for a light at its opposite end, said rigid support engaging member having a depending leg and a substantially horizontally disposed leg, and a strap attached to the outer end of said horizontally disposed leg and provided with a weight at its lower end heavier than the bracket and members supported thereby, said depending leg and strap being adapted to engage opposite sides of a support while the horizontally disposed leg engages the top of such support for holding the bracket firmly in the fixed position thereon, substantially as set forth.

In witness whereof, I have hereunto set my hand at Indianapolis, Indiana, this 19th day of August, A. D. nineteen hundred and twenty-six.

EDWARD E. HILL
